RING BOX

Nicholas Barbieri, Providence, R. I., assignor to Uncas Manufacturing Company, a corporation of Rhode Island

Application December 14, 1950, Serial No. 13,441

Term of patent 14 years

(Cl. D80—5)

To all whom it may concern:

Be it known, that I, Nicholas Barbieri, a citizen of the United States of America, residing at Providence, county of Providence, State of Rhode Island, have invented a new, original, and ornamental Design for a Ring Box, of which the following is a specification, reference being had to the accompanying drawings, forming a part thereof:

Fig. 1 is a perspective view of a ring box showing my new design;

Fig. 2 is a top plan view thereof; and

Fig. 3 is a bottom view thereof.

I claim:

The ornamental design for a ring box, substantially as shown.

NICHOLAS BARBIERI.
